UNITED STATES PATENT OFFICE

169,013

CHILD'S AUTO CHAIR

Ernest O. Musser, Grand Rapids, Mich.

Application October 8, 1951, Serial No. 16,870

Term of patent 14 years

(Cl. D15—1)

To all whom it may concern:

Be it known that I, Ernest O. Musser, a citizen of the United States, residing at Grand Rapids, in the county of Kent and State of Michigan, have invented a new, original, and ornamental Design for a Child's Auto Chair, of which the following is a specification, reference being had to the accompanying drawing, forming part thereof.

Fig. 1 is a perspective view of a child's auto chair showing my new design,

Fig. 2 is a side elevation thereof, and

Fig. 3 is a rear elevation thereof.

I claim:

The ornamental design for a child's auto chair, substantially as shown.

ERNEST O. MUSSER.
